UNITED STATES PATENT OFFICE.

JOHN S. MUCKLÉ, OF PHILADELPHIA, PENNSYLVANIA.

SAFETY DEVICE FOR ELEVATORS.

No. 893,349.

Specification of Letters Patent.

Patented July 14, 1908.

Application filed September 19, 1907. Serial No. 393,600.

To all whom it may concern:

Be it known that I, JOHN S. MUCKLÉ, a citizen of the United States, residing in Philadelphia, Pennsylvania, have invented certain improvements in Safety Devices for Elevators, of which the following is a specification.

My invention relates to certain improvements in means for stopping an elevator car should the hoisting rope break or the car become detached from the hoisting mechanism, or should the car run away due to a defect in the hoisting mechanism.

The main object of my invention is to simplify the construction of an apparatus of this type and make it dependent upon the velocity of the car in its descent to throw the mechanism into action.

A further object of the invention is to provide means for relieving the detainers, which are engaged by the hooks on the car, from severe strains to which they are subjected when an accident occurs.

In the accompanying drawings: Figure 1, is a section through the floor of an elevator car, illustrating my invention with the hooked members withdrawn, the car running at the ordinary speed; Fig. 2, is an enlarged view of a part of Fig. 1; Fig. 3, is a side view 30 of a detail of Fig. 1; Fig. 4, is a view showing the hook members thrown out, due to the rapid descent of the car; Fig. 5, is a view showing the hook members thrown out due to the breaking of the rope which operates 35 the mechanism; Fig. 6, is a view showing electric switch mechanism by which the electric hoisting mechanism is disconnected on the rapid descent of the car, and Fig. 7, is a view of a modification.

40 A is the floor of the car, B, B are the detainers which are engaged by the hooked members; these detainers consist, in the present instance, of two or more wire ropes b placed side by side and connected at intervals by cross bars b' bolted securely so as not to slide on the wire ropes, although, in some instances, they may be arranged to slide after being engaged by the hooked members.

45 The upper ends of the ropes are connected to a shock absorber C consisting in the present instance of a yoke c carrying a cylinder c' and a rod c² carrying a plunger c³, and on the lower end of the plunger is a flange c⁴ mounted between which and the end of the 50 cylinder is a spring c⁵, so that when the hooked members on the car engage the cross

bar b' the shock will be taken by the absorber, the spring c⁵ returning the cylinder to its normal position when released. In some instances a counterweight may be used in place of the cylinder and plunger.

Secured to the underside of the floor of the car are guides a, a in which slide the hooked members D, each hook member being forked as at d and so shaped as to engage the cross bar b' on the detainer. The hooked members may be pivoted to brackets on the car as shown in Fig. 7.

55 Mounted in the present instance under the center of the car floor is a frame E having 70 bearings e for a vertical shaft F on which is a grooved pulley or sheave f; around this pulley passes a rope n which extends throughout the length of the elevator shaft, being held at top and bottom by any suitable means. 75 This rope passes around two guide wheels n', n² on a bracket N secured to the underside of the elevator car. The movement of the car causes the shaft F to turn due to the fact that the ends of the rope are fixed. On the 80 shaft F is a sleeve H grooved at h and h'.

85 G is a governor having a hub g secured to the shaft F and projecting from the hub are two arms g' in the present instance, to which are pivoted the levers i, i. The long arms of these levers have balls i' at their extreme ends and the short arms rest in the groove h of the sleeve H, so that when the shaft F is rotated at a speed beyond the normal the balls will fly out causing the sleeve H to be drawn 90 down.

95 In order to operate the hooked members when the sleeve is drawn down I pivot two levers K, K at k to the frame E and one arm of each lever enters the groove h' in the sleeve 100 H and the other arm of each lever is connected by a rod k' to a hooked member D, as shown clearly in Fig. 1, so that when the sleeve is drawn down, due to the increased travel of the elevator car, the levers K, K 105 will be operated to force out the hooked members D, and these members will come in contact with the cross bar b' of the detainers B, as shown in Fig. 4, stopping the elevator car.

110 In order to stop the car in the event of the breaking of the rope n I pivot a lever M at m to the frame E and provide the lever with an idler m' which rests upon the rope n, as clearly illustrated in Fig. 1. This lever is heavy enough to force the sleeve H down against the weight of the balls so that

in the event of the rope *n* breaking, the lever *M* will fall, as shown in Fig. 5, forcing the sleeve *H* down and the hooked members *D* out into engagement with the detainers *B*.

In Fig. 6, I have shown an electric connection which may be used on electrically operated elevators so that when the sleeve *H* is lowered a switch *S* is thrown open, cutting off the electric connection. This is accomplished by attaching a rod *s* to one of the levers *K* which in turn is attached to the pivoted knife member *s'* of the switch *S* and there is a certain amount of lost motion owing to the slot and pin connection between the rod *s* and the lever *K* which will allow the lever to move nearly to its full extent without operating the switch, but on the last movement the rod *s* will be drawn down and the pivot member *s'* of the switch will be drawn away from the contact *s²*, as clearly shown in said Fig. 6.

There may be as many hooked members as desired according to the size and weight of the car, and the number and size of ropes in the detainers will depend upon the weight of the car.

It will be seen that by setting the governor balis so that they will only operate the sleeve when the car descends at a speed greater than the normal speed, I am enabled to run the car entirely free of any of the mechanism; the hooked members being retracted within the line of the car and the detainers are situated in the elevator well one on each side of the car and clear of any of the mechanism of the car.

If the hoisting mechanism should become disarranged or broken and should allow the car to fall then the governor would be driven at an increased rate of speed and would draw the sleeve down and force the hooked members out into engagement with the cross bars of the detainers, stopping the car before any damage could be done. The stoppage would be comparatively gradual due to the fact that the detainers are suspended from shock absorbers. On reversing the car the hooked members automatically return to their normal positions as they will be forced out of engagement with the cross bars of the detainers.

I claim:-

1. The combination in an elevator, of a car, detainers in the elevator well free of the car, each detainer consisting of a vertical member having one or more cross bars, a frame mounted under the car, a ball governor carried by the frame, a rope in the well adapted to drive the ball governor, hooked members mounted on the under side of the car and connected directly with the governor so that when the downward movement of the car exceeds the normal speed the hooked members will be projected to engage the cross bars of the detainers and on the reversal of the movement of the car the hooked members will be

automatically retracted from the cross bars of the detainers, substantially as described.

2. The combination in an elevator car, of a frame centrally mounted on the car, a vertical shaft on the frame, a governor carried by the shaft, a sheave secured to the shaft, a rope fixed in the elevator well passing around the sheave on the shaft, a sleeve on the shaft actuated by the governor, two hooked members, two levers, and means for connecting the hooked members with the levers, said levers being actuated by the sleeve, substantially as described.

3. The combination of an elevator car, a frame mounted under the car, a shaft adapted to bearings in the frame, a sheave on the shaft, arms secured to the shaft, weighted levers pivoted to the arms, a sleeve mounted on the shaft, two grooves in the sleeve, one groove adapted to receive the short arms of the weighted levers, a pair of levers, one arm of each lever entering the other groove in the sleeve, sliding hooked members, rods connecting the said hooked members with the last mentioned levers, a detainer on each side of the car arranged to be engaged by the hooked members, when forced out by the action of the weighted levers when the car exceeds the normal speed, and a rope secured in the elevator well and passing around the shaft carried by the car, substantially as described.

4. The combination of an elevator car, a frame a shaft, a governor mounted on the shaft, a rope sheave also mounted on the shaft, a rope fixed in the well and passing around the sheave on the shaft, a sleeve mounted on the shaft and actuated by the governor, a lever pivoted to the frame, and controlled by the sleeve, a hooked member mounted on the car, and connected to the last mentioned lever, a detainer mounted in the elevator well arranged to be engaged by the hooked member when projected, a lever pivoted to the frame and having an idler resting on the rope which passes around the sheave, said lever being so situated with respect to the sleeve that in the event of the breaking of the rope the lever will fall and force the sleeve down throwing the hooked member out and into engagement with the detainer, substantially as described.

5. The combination of an elevator car, a frame under the car, a vertical shaft on the frame, a rope sheave on the shaft, a governor actuated by the shaft, a sleeve on the shaft with which the governor engages, a hooked member under the car, a lever connected to the hooked member having an arm engaging the sleeve, a detainer mounted in the elevator well having a cross bar with which the hooked member engages, and a shock absorber connected to the detainer for allowing the detainer to yield when engaged by the hooked member, substantially as described.

6. The combination of a car, a frame secured to the under side of the car, a vertical shaft mounted in bearings on the frame, a rope sheave secured to the shaft, and a governor also secured to the shaft, two guide wheels mounted on the car, a rope fixed in the elevator well and passing around the guide wheels and around the sheave on the vertical shaft, two detainers mounted in the elevator well, two hooked members mounted on the under side of the car, and arranged to engage the detainers when moved outwards, a sleeve on the vertical shaft engaged by the governor, and two levers pivoted to the frame one arm of each lever being engaged by the sleeve and a rod connecting the other arm of each lever to a hooked member, a lever pivoted to the frame and resting directly above the sleeve and an idler on the lever resting upon the rope leading to the sheave on the vertical shaft, substantially as described.

7. The combination in an elevator, of a car, a frame mounted on the car, a shaft mounted on bearings on the frame a governor on the shaft, a rope sheave on the shaft, a rope mounted in the well and passing around the sheave so as to drive the shaft as the car is raised or lowered, a lever on the frame connected to the governor mechanism, a hooked member connected to the lever and arranged to engage a detaining device in the elevator well, an electric switch, a rod connecting the electric switch with the lever so that when the governor forces the hooked member out into engagement with the detainer, it will also open the switch and break the electric circuit, substantially as described.

8. The combination of an elevator car, a frame mounted on the underside of the car, 40 bearings on the frame, a vertical shaft mounted in the bearings, a sheave mounted on the shaft, a rope attached to fixed points in the elevator well, two idlers mounted on one side of the car, one under 45 the other, said rope passing around the idlers and around the sheave on the vertical shaft, a sleeve on the vertical shaft having two grooves, a hub secured to the lower end of the shaft and having arms, levers pivoted 50 to the arms and arranged to enter one of the grooves in the sleeve, said levers being weighted, and levers pivoted to the frame having arms entering the other groove in the sleeve, slideways on the underside of the 55 car, hooked members arranged to slide in said ways, rods connecting the hooked members with the last mentioned levers, an arm pivoted to the frame and resting above the sleeve, an idler on said arm resting on 60 the rope that passes around the sheave on the vertical shaft, a detainer in the well on each side of the car, said detainer consisting of ropes and cross bars on said ropes to be engaged by the hooked members on the car, 65 and shock absorbers attached to the upper ends of the detainers, substantially as described.

In testimony whereof, I have signed my name to this specification, in the presence of 70 two subscribing witnesses.

JOHN S. MUCKLE.
